CLAIM

The ornamental design for a pillow with border of interleaved fins, as shown and described.

DESCRIPTION

FIG. 1 is a front elevational view of a pillow with border of interleaved fins showing my new design;

FIG. 2 is a top plan view thereof with side views and a bottom plan view being identical; and,

FIG. 3 is an enlarged fragmentary front elevational view of a pair of interleaved fins shown separately for clarity of illustration and with the rear being identical.

FIG. 1

FIG. 3
